UNITED STATES PATENT OFFICE.

MARTIN JELALIAN, OF CRANSTON, RHODE ISLAND.

HAND-POWER-PROPELLED HYDROAERO SPORTING DIRIGIBLE BALLOON.

1,247,960.

Specification of Letters Patent. Patented Nov. 27, 1917.

Application filed April 18, 1917. Serial No. 162,993.

To all whom it may concern:

Be it known that I, MARTIN JELALIAN, a citizen of the United States, residing at the city of Cranston, in the county of Providence and State of Rhode Island, have invented certain new and useful Improvements in Hand - Power - Propelled Hydroaero Sporting Dirigible Balloons, of which the following is a specification.

10 The object of the invention is to provide new and useful improvements in aerial apparatus of that class that are essentially designed for amusement purposes, and having a gas bag capable of lifting and sustaining 15 the ship and constituting a pair of arm power operated wings to assist in lifting and to propel the ship forward.

The apparatus being provided with cylinders arranged at the bottom thereof in 20 order to easily permit the latter to float upon the surface of the water when traveling on the water.

The invention consists in the special features of the construction and combination of 25 parts, as hereinafter described and claimed.

In describing the invention in detail reference is had to the accompanying two sheets of drawings, in which:—

Figure 1 is a side elevation of my improved apparatus, showing one form of balloon or gas bag for the same; Fig. 2 is a front elevation of the apparatus, as equipped with another form of balloon; Fig. 3 is a plan view of the main plane, showing the 35 same as provided with a wire netting; Fig. 4 is a detail view of the winged device. Fig. 5 is a hand-support designed to operate the wings. Fig. 6 is a flat circular support for the wings adapted to receive the end portions of connecting ropes.

Referring to the drawings, the numeral 1— designates a gas bag. To reinforce said gas bag and prevent the same from collapsing, connecting ropes 2 and 3 are used 45 which extend transversely to the gas bag 1— and surround the upper portion of the same. Ropes 4, 4— extend from the lower ends of said connecting ropes 2 and 3 from each side of the gas bag 1— and have their 50 lower ends connected to the perforations

—5, 5— formed at the upper portion of a ring 6—. Said ring 6— also has equi-spaced perforations 6¹, 6²— at the lower part thereof to receive the upper ends of the suspension ropes 8, 8— and the lower ends 55 of said suspension ropes 8, 8— are provided with snap-hooks and attached to the eyelets 22, 22— secured upon the top of the car 11—.

The ring 6— also has a central inwardly 60 projecting circumferential portion 5²— provided with equi-spaced perforations encircling the same and adapted to receive a wire netting 5¹— and a canvas 6²— is secured upon the top and bottom of the latter in order to serve as a plane for the apparatus.

The car 11— which has a rectangular top and bottom connected by vertical supports 11¹, 11²— carries a pair of bird-like 70 wings 16¹, 16²—, which have their inner ends pivotally connected upon each side of the top of the car 11—, as at 16², 16²—, and extend outwardly therefrom. The top of the car 11— has a wire netting 16⁵— 75 and canvas secured upon the top and bottom of the latter so as to serve as a plane, and the wings 16¹, 16²— in operation force the air directly beneath the same thereby giving an additional buoyancy to the apparatus. 80

Extending outwardly from the rear end of the top plane of the car 11— is a laterally projecting tail portion 12¹— designed to react against the atmosphere. The bottom of the car 11— is also provided with a 85 wire netting and canvas in the same manner as the top to react against the atmosphere.

The gas bag 1— is provided with a flexible tube connection 9¹— and said tube connection projects through the main plane 90 6—, and thence passes through the top of the car 11— adjacent to the operators, and has a suitable valve to permit the gas to escape from the latter.

The wings 16¹, 16²— which are pivotally connected centrally to each side of the upper plane of the car 11— are each provided with a flat circular support 17— located centrally beneath the same, and said supports 17, 17— have equi-spaced perfo- 100

rations —18⁵, 18⁵— encircling the same and adapted to receive the lower ends of connection ropes —17¹, 17¹— and the opposite ends of said ropes —17¹, 17¹— are connected to 5 the transverse wing supports —25, 25—. A wire netting is carried by said supports —25, 25— and canvas secured upon the top and bottom of the latter, as shown in Fig. 1.

Main connection ropes —17²— for each of 10 said wings —16¹, 16¹— have one of their ends connected centrally upon the bottom of the circular support —17, 17—, as at points —17⁶, 17⁶—, and the opposite ends thereof attached to the upper ends of a hand operated 15 T shaped support —17⁴— which is provided with an eyelet —25¹— at each end of its transverse portion —25²—, as shown in Figs. 1, 2, 4 and 5. Secured centrally upon each side of the top of the car —11— are 20 vertical supports —17⁵, 17⁵—, and coil pull-springs —18¹, 18¹— have one of their ends secured to the upper ends of said vertical supports —17⁵, 17⁵— and the lower ends thereof attached to the eyelets —18², 18²— 25 integral with the wings —16¹, 16¹—, and said pull-springs are designed to assist the upward movement of the wings.

Projecting outwardly from each side of the bottom plane of the car —11— are supporting planes —14, 14— which are integral 30 with and extending outwardly therefrom; cylinders —15¹, 15¹—, provided with straps —15², 15²— are secured upon the bottoms of said outwardly extending planes —14, 35 14— and said cylinders are designed to float upon the surface of the water when traveling upon the water. The bottom plane of the car —11— also carries a pair of oppositely arranged seats, provided with suitable straps for securing the operators thereto.

A series of supports —19, 19— extend from the bottom of the car —11— to a converging position and have supporting wheels —19¹, 19¹— secured at the lower ends thereof.

The operation of the device will be readily understood, and it will be obvious that by the arrangement described the apparatus can be operated and controlled in a most safe and successful manner.

Thus describing my invention what I claim as new and desire to secure by Letters Patent, is:—

1. An apparatus of the character described comprising an arm power propelled car having a rectangular-shaped top and bottom to serve as planes, a pair of bird-like wings pivotally connected to each side of the upper plane of said car and extending outwardly therefrom, pull-spring connections arranged upon said wings and said pull-spring connections designed to facilitate the upward movement of said wings, said wings carrying a series of equi-spaced transversely extending supports, a wire net-

ting secured to the latter and canvas carried upon the top and bottom of the netting, means for operating said wings, and the same when in operation force the air directly beneath the top plane of said car.

2. An apparatus of the character described comprising an arm power propelled car having a rectangular-shaped top and bottom to serve as planes, said top and bottom of said car made of closely woven fine wires and canvas secured to the latter, a series of integral hooks carried by the top plane of said car and arranged upon the top of the same, supporting wheels secured beneath the bottom plane of the car; and an outwardly extending tail portion projecting from the rear end of the top plane of the latter.

3. An apparatus of the character described comprising an arm power propelled car having a flat top and bottom to serve as planes, a pair of lateral bird-like wings having their inner ends pivotally connected to each side of the top plane of said car and extending outwardly therefrom, a flat circular support for each of said wings and said supports provided with perforations encircling the same, a series of wing ropes having one of their ends secured to the perforations of said circular supports and the opposite ends thereof attached to the wings, a main rope for each of said wings and having one of its ends connected centrally upon the bottom of said circular supports and the opposite ends thereof attached to the upper ends of a hand operated T shaped support, and means to operate said wings by pulling the lower end of said T shaped support.

4. An apparatus of the character described comprising an arm power propelled car having a rectangular-shaped top and bottom to serve as planes, and said bottom of the car having outwardly extending planes integral with and projecting outwardly from each side thereof, cylinders carried beneath said outwardly extending planes and provided with straps for securing said cylinders thereto, and said cylinders adapted to receive air under pressure and thereby provide buoyancy to said planes.

5. An apparatus of the character described comprising a gas bag carrying a main plane suspended therefrom, said plane consisting of a ring having a flat outer surface and also a central inwardly projecting circumferential portion provided with equi-spaced perforations, a wire netting secured to the latter and a layer of canvas secured upon the top and bottom of the netting, said ring provided with perforations encircling at the upper and lower ends thereof, rope connections from the bag having their ends secured to the perforations of the upper end of said ring, rope connections ex-

tending from the perforations of the lower end of the ring and the free ends thereof having snap-hooks and attached upon the top of a car carried by said gas bag, a flexible tube extending from said gas bag and projecting centrally through said plane and thence passing through the top plane of the car adjacent to the operators, and a suitable valve connection within easy reach of

the same to permit the gas to escape from 16 said tube.

In testimony whereof I affix my signature in presence of two witnesses.

MARTIN JELALIAN.
